PRESS MECHANISM

Richard W. Dinzl, Philadelphia, Pa., assignor,
by mesne assignments, to Baldwin-Southwark
Corporation, a corporation of Delaware

Application January 8, 1931, Serial No. 507,498

11 Claims. (Cl. 153—10)

My invention relates to press mechanism, and the object of my invention is to provide a fluid-operated press particularly adapted for the crushing or compacting of material,—large diameter 5 pipe sections, for instance,—for easier handling.

My invention includes a press which may have plates between which the material may be crushed or compacted; one of said plates being fixed to the cross-head and the other being hinged to the 10 press platen so as to be capable of movement with respect to the platen when the latter is lowered after a compressing or compacting operation. In some instances it may be possible or desirable to omit the plate carried by the cross-head.

15 My invention includes a hook designed to be pushed out of the way when the press platen rises, so that such hook may engage a lug or projection, preferably a roller, carried by the movable plate supported by the press platen, and sustain the 20 same at one end while its opposite end, hinged to the platen, lowers. By this means, material crushed between the press platen and cross-head or the plates carried thereby may be automatically discharged from the hinged plate as it inclines 25 while one end is temporarily supported by the hook as the press platen lowers.

A further object of my invention is to provide 30 cushioning means for the hinged plate so that it may lower gradually upon the press platen, after it has been released from the hook.

These and other features of my invention are more fully described hereinafter, reference being had to the accompanying drawing, more or less diagrammatic in character, in which:

Figure 1 is a front elevation, partly in section, of a press having and containing the features forming the subject of my invention;

Fig. 2 is a side elevation, with portions partly broken away to show clearly details comprising 40 my invention;

Fig. 3 is an enlarged sectional view illustrating a detail of my invention; and

Fig. 4 is a sectional plan view on the line IV—IV, Fig. 3.

In the crushing or compacting of various materials for many purposes, press mechanism of some type is usually employed. In the present instance I have shown a press which may be employed for compacting large pipe sections, having 45 a base 1, with cylinder 2, containing a ram 3, (hollow in the present instance) connected to a platen 4. Columns 5, upon which said platen may be guided, connect the base of the press with a cross-head 6, and this cross-head, in the present instance, carries pull-back cylinders 7, having

rams 8; the latter being connected to the platen 4 and operated in any usual manner.

The cross-head carries a plate 10, which may be fixed thereto, and the press platen 4 carries a plate 11, which may be hinged thereto at 11^a, and between these plates 10 and 11, the material may be crushed or compacted. In some instances the plate 10 may be omitted and the material may be compressed against the under face of the cross-head. The lift of the press platen during such 10 crushing operation may be as high as the line X—X, Fig. 2.

The plate 11 carried by the press platen is provided with a lug or other projection, preferably a roller 12, at one end of the same, as clearly 15 indicated in Figs. 1 and 2 of the drawing. The cross-head 6 carries a hook 13, pivotally mounted at 14, and having an overbalancing portion 13^a so that its normal position is that indicated in Fig. 2.

When the plate 11 is raised by the press platen, the roller 12 carried thereby engages the lower cam face of the hook 13 and pushes the same out of the way, so that as the press platen continues to or near the limit of its upward movement, the 25 hook will underlie the roller 12 of the plate 11, and serve as a temporary support for such end of the plate for a short period while the press platen 4 is descending. When the press platen lowers, after a crushing or compacting operation, the 30 plate 11 will lag back and move on its hinge connection 11^a, as indicated by broken lines, Fig. 2; the inclination being such as to automatically discharge the crushed or compacted mass from the same; which may pass to a suitable conveyor, or be otherwise disposed of.

As soon as the press platen lowers to an extent sufficient to allow the plate 11 to leave the hook, such plate will drop back upon the press platen. Unless cushioned, this action would be more or less objectionable, on account of noise and possible displacement of the plate, and I provide 40 means permitting the plate 11 to move back to the press platen in an easy and gradual manner.

To this end, the hollow ram 3 may carry a cylinder 15 containing oil and in which a piston 16 is arranged; the latter being carried by a rod 17, connected by links 18 to the plate 11, which may have a lug 11^b for such connection. When the hook 13 is in engagement with the roller 12 of the plate 11 as the press platen descends, the piston 16 will be raised in its cylinder, and as soon as the hook releases the plate 11, the piston is free to fall in its cylinder; displacing the oil therein which bleeds through the piston; thereby

providing sufficient and proper resistance to insure movement of said plate 11 without clatter or disarrangement.

To this end the piston 16 may be constructed and arranged as shown in Fig. 3. In such view the rod 17 as shown as having a reduced end 17^a carrying the piston 16, which is perforated, as indicated at 16^a, and provided with a groove communicating with such perforations. The piston 10 is held in place by a nut 19 spaced therefrom by a collar 20, and a plate 21 underlying the piston is loosely mounted on this collar. The plate 21 may also be perforated, as indicated at 21^a; the perforations of the same being smaller than the 15 perforations 16^a of the piston. When the piston is lifted, the plate 21 is held back by the oil freely passing through the perforations of the piston and out between the bottom of the same and the plate 21. When the piston is lowered the smaller 20 bleeding holes in said plate 21 slow down the movement of the piston so that the lowering is gradual; thereby assuring easy return of the hinged plate 11 to its normal position on the press platen.

25 While I have shown the cylinder 16 as located within the hollow ram and supported by the same it is obvious that such cylinder might be mounted externally thereof and conveniently supported by the press platen; the plate 11, in such instance, 30 having an extension at the rear of the press as indicated by dotted lines in Fig. 2, or otherwise disposed so as to provide proper connection with the piston rod disposed in such cylinder, and such arrangement is within the scope of my invention.

35 I claim:

1. The combination with press mechanism including a movable press platen and means for imparting vertical movement thereto, of a flat plate overlying said movable press platen and hinged thereto at one side of the same, and self-releasing means attached to an upper stationary portion of said press mechanism for tilting said plate with respect to its hinged connection with the movable press platen as the latter starts to lower from the limit of its upward movement.

2. The combination with press mechanism, including a cross-head, a vertically reciprocable press platen, and means for imparting upward movement to said press platen, a flat plate overlying said press platen and hinged thereto at one side of the same, and self-releasing means carried by said cross-head for tilting said plate with respect to its hinged connection with said press platen as the latter starts to lower from the limit of its upward movement.

3. The combination with press mechanism including a movable press platen and means for imparting upward movement thereto, of a flat plate overlying said press platen and hinged thereto at one side of the same, and a self-releasing hook pivotally hung from the upper part of the press mechanism and adapted to engage said plate at one side and tilt the same with respect to its hinged connection with the press platen as the latter starts to lower from the limit of its upward movement.

4. The combination with press mechanism, including a cross-head, a vertically reciprocable press platen and means for imparting upward movement thereto, of a plate hinged to said press platen, and a hook carried by said cross-head and adapted to engage said plate at one end and cause it to tilt with respect to its hinged connection as the platen starts to lower from the limit of its upward movement.

5. The combination with press mechanism including a movable press platen and means for imparting vertical movement thereto, of a flat plate overlying said press platen and hinged thereto at one side of the same, self-releasing means for tilting said plate with respect to its hinged connection with the platen as the latter starts to lower from the limit of its upward movement, and means for cushioning the movement of said plate into contact with the plate when 10 said tilting means releases the plate.

6. The combination with press mechanism including a movable press platen and means for imparting vertical movement thereto, of a flat plate overlying said press platen and hinged thereto at one side of the same, self-releasing means for tilting said plate with respect to its hinged connection with the platen as the latter starts to lower from the limit of its upward movement, and means for cushioning the movement 15 of said plate into contact with the platen when said tilting means is released; said cushioning means including a cylinder operatively connected to the press platen, and a piston in said cylinder operatively connected to said hinged plate.

25 7. The combination with press mechanism, including a base, a cylinder, a movable platen, a cross-head, and connecting parts, of a plate hinged to the platen between which and the cross-head material may be compacted, and a pivotally mounted hook carried by the cross-head and adapted to engage said hinged plate when the latter reaches the limit of its upward movement; said hook temporarily sustaining said plate whereby it may tilt and automatically discharge 35 the compacted body.

8. The combination with press mechanism, including a base, a cylinder, a movable platen, a cross-head, and connecting parts, of a plate hinged to the platen between which and the cross-head material may be compacted, a pivotally mounted hook carried by the cross-head and adapted to engage said hinged plate when the latter reaches the limit of its upward movement; said hook temporarily sustaining said plate 40 whereby it may tilt and automatically discharge the compressed body, and means operatively connected to the press platen for cushioning the return movement of said plate.

45 9. The combination with press mechanism, including a base, a cylinder, a movable platen, a cross-head, and connecting parts, of a plate hinged to the platen between which and the cross-head material may be compacted, a pivotally mounted hook carried by the cross-head and adapted to engage said hinged plate when the latter reaches the limit of its upward movement; said hook temporarily sustaining said plate whereby it may tilt and automatically discharge the compressed body, and means carried by the press 55 platen for cushioning the return movement of said plate.

10. The combination with press mechanism, including a base, a cylinder, a movable platen, a cross-head, and connecting parts, of a plate 65 hinged to the platen between which and the cross-head material may be crushed, a pivotally mounted hook carried by the cross-head and adapted to engage said hinged plate when the latter reaches the limit of its upward movement; said hook temporarily sustaining said plate whereby it may tilt and automatically discharge the compressed body, a supplemental cylinder operatively connected to the press platen, and a piston mounted in said supplemental cylinder and oper- 70

atively connected to said hinged plate for cushioning the return movement of the same.

11. The combination with press mechanism, including a base, a cylinder, a ram therein, a movable platen connected to said ram, a cross-head, and connecting parts, of a plate hinged to the platen between which and the cross-head material may be crushed, a pivotally mounted hook carried by the cross-head and adapted to engage

said hinged plate when the latter reaches the limit of its upward movement; said hook temporarily sustaining said plate whereby it may tilt and automatically discharge the compressed body, a supplemental cylinder carried by the ram, and a piston mounted in said supplemental cylinder and operatively connected to said hinged plate for cushioning the return movement of the same.
